GATE

Harm Ahlrichs, Petersburg, III.

Application April 10, 1941, Serial No. 387,950

1 Claim. (Cl. 39—56)

This invention has reference to gates and more particularly to such gates as are equipped with mechanism to be operated remote from the gate for changing the center of gravity of the gate so as to cause it to swing by its own weight into and out of closed position.

An object of the present invention is to improve generally upon such types of gates and particularly to provide improved mounting means for the gate including means permitting vertical shifting movement of the gate and additional means for holding the gate in raised position to permit animals and the like to pass thereunder even when the gate is in closed position.

Further in accordance with the present invention means is provided whereby when the gate is in raised closed position, the operating mechanism therefor will still be operable to release the gate so as to permit the same to swing by its own weight into an open position.

Further in accordance with the present invention means is provided for releasably holding the gate in an open position with the operating mechanism of the gate remaining operable to release the gate from this open position and cause it by its own weight to return to closed position.

The invention together with its objects and advantages will be best understood from a study of the following description taken in connection with the accompanying drawings wherein:

Figure 1 is a top plan view showing somewhat diagrammatically my improved gate and operating mechanism therefor and with the gate shown in closed position by full lines and in open position by broken lines.

Figure 2 is a view showing the gate in open position but with the keeper-equipped post holding the gate in open position removed.

Figure 3 is an elevational view of the gate in a closed position and also in lowered position.

Figure 4 is an enlarged view partly in section and partly in elevation showing the hinge assembly for the gate.

Figure 5 is an enlarged fragmentary side elevational view showing the mechanism for holding the gate in a raised position.

Figure 6 is a perspective view of the bottom hinge rod and associated parts.

Figure 7 is a perspective view of an operating crank, and

Figure 8 is a fragmentary horizontal sectional view through a post and the top hinge bracket associated therewith.

Referring more in detail to the drawings it will be seen that in the preferred embodiment of the invention there is provided a hinge post 5 on which are mounted vertically spaced hinge brackets 6, 7.

Journalized in the hinge bracket 6 is a vertical hinge pin 8 that extends through the upper and lower arms of the bracket 6 and through a fixed hinge plate 9 bolted or otherwise secured on an upper corner of the gate 10 as shown.

Journalized vertically in the lower hinge bracket 7 is an angular or crank-form of hinge pin 11 that also extends through the apertured part of the hinge plate 12 suitably mounted adjacent the lower edge of the gate 10.

The hinge rod 11 embodies the aforementioned crank portion 11a and an integral shank portion 11b.

For the lower free end of the shank or shaft portion 11b of the hinge rod 11 there is suitably provided a stationary bearing 13.

Fixedly secured on the shank or shaft portion 11b of the hinge rod 11 is a disk 14 that is provided adjacent its peripheral edges with oppositely disposed apertures that accommodate the angular ends 15, 16 of rods 15a and 16a, respectively.

The rods 15a, 16a have ends thereof pivotally connected with arms 17a and 18a, respectively, of cranks 17 and 18, respectively, disposed at opposite sides of the gate as shown in Figure 1 so as to, respectively, transmit movement of one of the cranks to the disk 14 and consequently the hinge rod 11 for causing the gate 10 to swing to an open or closed position, as the case may be.

At the side of the entrance controlled by the gate 10, opposite to that side thereof where the post 5 is located, there is located a post 19 on which is suitably mounted a spring-keeper assembly 20 with which is cooperable a spring latch 21 on the free end of the gate 10 for holding the gate releasably secured in closed position.

The post 19 is also provided with a suitable stop 22 disposed at right angles to the keeper 20 and cooperable therewith for releasably retaining the gate 10, in closed position, and against untoward swinging in either direction.

Also in accordance with the present invention a third post 23 is provided and the same is arranged at one side of the driveway in a somewhat triangular relationship to the posts 5 and 19 and, as shown in Figure 5, when the gate 10 is swung to open position it will, when in open position, abut the post 23. Post 23 is also provided with

a suitable spring keeper assembly 24 with which the spring latch 21 of the gate 10 is cooperable for releasably holding the gate in this open position suggested by broken lines in Figure 1.

The gate is operated by a vehicle or otherwise at a point remote from the gate in the following manner: Assuming that the gate is in the closed position shown in Figure 1. A vehicle approaching the gate from the right side, as viewed in Figure 1, will ride over the raised portion of the crank 18 rocking the same in its bearings and exerting a push on the rod 16a. This will cause the disk 14 and associated hinge rod 11a to rotate, and this rotative movement of the hinge element 11 will cause a slight "lifting" of the gate 10 so as to free the spring latch 21. As a result the upper part of the gate is moved out of vertical line with the bottom so that the gate will then of its own weight swing into the open position suggested by dotted lines in Figure 1 and become latched to the post 23.

The movement just described for crank 17 will move the rod 16a causing the disk 14 and hinge pin or rod 11 to turn in a reverse direction so that, as aforementioned, the gate 10 will be raised slightly to release the latch 21 thereof from the keeper 24 and to cause the gate of its own weight to then swing from the open position suggested by dotted lines in Figure 1 to the closed position suggested by full lines in Figure 1 and become latched to the post 19 in this closed position.

Thus, in this way, the gate is released and moved to a closed position behind the vehicle passing through the gateway.

It will be appreciated that the gate-operating means may be actuated by a vehicle approaching from either direction.

It will also be appreciated that the gate, so hinged and hung, may be used as an ordinary farm or walk gate, the gate being also freely swingable with respect to the hinge elements 8 and 11.

Further in accordance with the present invention, means is provided for retaining the gate in an elevated position to clear snow drifts or to allow small animals to pass therebeneath. To that end there is provided a retaining element 25 which, in the present instance, is in the form of a flat plate having at one end a laterally directed apertured ear 26 through which the hinge pin 8 extends, and is positioned on the hinge pin be-

tween the lower member of the hinge bracket 6 and the apertured ear of the hinge plate 9 secured to the gate 10 as shown in Figure 4. At the opposite end thereof the member 25 is provided with a narrow extension 26 which serves as a handle therefor, and a relatively short teat 27 that is adapted to be engaged in an aperture 28 provided therefor in the bottom member of the bracket 6 as shown in Figure 8.

Thus, to retain the gate 10 in a raised or elevated position, the gate 10 is slid upwardly and the operator then raises the member 25 so as to engage the teat 27 in the aperture 28 of the bracket 6, so that the parts are then substantially in the position shown in Figure 5, and in which position the member 25 serves to retain the gate in this raised or elevated position.

It will also be understood that when in such raised or elevated position the gate may still be operated by remote control through the gate-operating mechanism hereinbefore described, and that also the gate when in elevated or raised position may be used as an ordinary farm or walk gate.

It is thought that the invention, together with its many advantages, will be clear to those skilled in the art.

It is also to be understood that I do not wish to limit myself to the precise embodiment of the invention as herein illustrated since changes may be made therein by persons skilled in the art to which the invention relates.

Having thus described the invention what is claimed as new is:

In a gate structure including a gate and a post, a bracket connected with the post and having outwardly extending arms, a vertically arranged crank pin journaled in the arms by straight end portions, the lower end portion being extended to pass downwardly well beyond the lower arm of the bracket, a stationary bearing supported in the gateway and into which the said extended lower end of the crank pin extends, a bracket on the gate having an outwardly extending part formed with a hole for receiving the crank part of the pin, a disk connected with the extended lower end of the pin and resting on the bearing, rods connecting the said disk and extending in opposite directions, and wheel operated cranks operatively connected to said rods.

HARM AHLRICHES.
